UNITED STATES PATENT OFFICE.

AUSTIN G. WHITE, OF MORGANTOWN, WEST VIRGINIA, ASSIGNOR TO THE STATES COMPANY, A CORPORATION OF CONNECTICUT.

WIRE CLAMP.

Application filed January 25, 1927. Serial No. 163,366.

This invention relates to a clamp which is particularly adapted for making test and temporary electrical connections with heavy wires and cables, but, of course, it may be employed for other purposes, especially where a plurality of wire junctions are required.

The object of the invention is to provide a simple, inexpensive and strong clamp which can be employed to connect the terminals of 10 one or more wires together, or two continuous line wires or cables.

The embodiment of the invention illustrated has an insulating block with a conducting plate on one face and a conducting 15 yoke that is adjustable toward and from the plate, the yoke having limbs that enter openings in the block to guide and prevent it from turning, and also having a threaded stem that extends through the block, and 20 on the side opposite the yoke has a nut whereby a wire or wires may be clamped between the nut and the block or between the yoke and plate, or both, by simply turning the nut down.

25 In the accompanying drawings Fig. 1 shows a side elevation of the clamp. Fig. 2 is an edge view showing a wire clamped between the nut and block. Fig. 3 shows a bottom view with the terminals of two wires 30 clamped between the yoke and block. Fig. 4 is a top view with the device clamped upon a continuous wire.

The block 1 may be made of porcelain or any other suitable insulating material with 35 a central perforation 2 and openings 3 on each side of the center. A conducting plate 4 with a perforation that aligns with the central perforation and openings that align with the side openings is attached to the 40 under side of the block. The yoke 5 is made of conducting material with its upwardly extending limbs 6 loosely fitting the openings in the block. A stud 7 extends upward from the center of the yoke through the 45 perforation in the block, and a thumb nut 8 is secured on the threaded upper end of the stem. When the nut is turned down either upon a wire or against the top of the block the yoke is drawn up against a wire 50 or the plate attached to the bottom of the block.

With this device the terminals or the exposed sections of one or more wires may be clamped between the nut and the top of the

block, or between the yoke and the bottom 55 of the block, that is, one or more wires may be clamped above or one or more wires may be clamped beneath or both, as the circumstances require. The yoke can be disengaged from the block to permit the introduction 60 between its limbs of a continuous wire or cable and when reassembled with the block a tap wire or test wires may be electrically connected therewith through the nut and stem, if desired. The limbs entering the 65 openings in the block guide the yoke in its movements and hold it from twisting when the nut is turned, also prevent it from breaking or the limbs from opening out so as to become disengaged from, or allow the disengagement of, any wire or cable to which the clamp is attached.

The invention claimed is:

1. A wire clamp comprising a block of insulating material having a central perforation and openings on each side of the perforation, a yoke of conducting material having limbs extending into said openings and having a threaded stem projecting through said perforation, a nut threaded on 80 said stem, and a conducting plate attached to said block and facing said yoke.

2. A wire clamp comprising a block of insulating material, a yoke formed of conducting material removably attached to said 85 block, said yoke having integral limbs that extend into said block and form confined spaces for retaining wire between the limbs of the yoke and the block when the parts are assembled, said yoke also having an integral threaded stem that projects through the block and a nut threaded upon said stem and adapted to be screwed against the side of the block opposite from the yoke.

3. A wire clamp comprising a block of insulating material having a central perforation and openings on two sides of said perforation, a metallic yoke having a central threaded metallic stem projecting through said perforation and also having metallic 95 limbs extending into said openings and forming confined spaces for retaining wire between the limbs of the yoke and the block when the parts are assembled, and a metallic thumb nut threaded upon the end of said 100 stem.

4. A wire clamp comprising a block of insulation having a central circular perfora-

tion and rectangular perforations each side of and parallel with said central perforation, a conducting yoke having a central stem extending through said central perforation 5 and having angular limbs parallel with said stem and extending loosely into said rectangular perforations and forming confined spaces for retaining wire between the limbs of the yoke and the block when the parts are assembled, and a metallic nut threaded upon said stem and adapted to be turned 10 against said block.

AUSTIN G. WHITE.
